UNITED STATES PATENT OFFICE.

EMIL A. KOPE, OF NEWARK, NEW JERSEY, ASSIGNOR TO THE SINGER MANUFACTURING COMPANY, A CORPORATION OF NEW JERSEY.

HINGE.

Application filed August 12, 1919. Serial No. 317,071.

To all whom it may concern:

Be it known that I, EMIL A. KOPE, a citizen of the United States, residing at Newark, in the county of Essex and State of New Jersey, have invented certain new and useful Improvements in Hinges, of which the following is a specification, reference being had therein to the accompanying drawings.

This invention relates to hinges, more particularly of the so-called "flush-type" and has for an object to provide a hinge which is particularly adapted for the folding or cover leaf of a drop-head sewing machine cabinet and which will permit said leaf to be opened thru an angle of substantially 270°.

Another object of the invention is to provide a hinge which may be set substantially flush with the exposed surfaces of the cabinet-top and cover and which will not offer any objectionable or unsightly protuberances in either closed or open position.

A further object of the invention is to provide a hinge which will permit the cover-leaf to be opened or swung through an angle of 270° from a horizontal position upon the cabinet-top to a pendant vertical position at one end of the cabinet-top, and at the same time dropped so that its upper edge will not project above the level of the upper surface of the cabinet-top.

Still further, the invention has for an object to provide a hinge which will effect the elevation of the hinge-end of the cover-leaf as said leaf is being closed, thereby preventing damage due to rubbing or other harsh contacts between the cover-leaf and cabinet-top.

With the above and other objects in view, as will hereinafter appear, the present hinge comprises a pair of hinge-leaves each of which is preferably formed of bent sheet-metal and comprises a pair of spaced vertical walls and horizontal attaching ears. The spaced walls of the hinge-leaves 45 embrace the opposite ends of a distance link which permits the cover of the cabinet to drop as it is being opened out so that its upper edge will not project above the level of the exposed surface of the cabinet-top. The stationary leaf member of the hinge, i.e., the one which is secured to the cabinet-top, is provided at the upper edges of the spaced vertical walls with very slight up-

ward extensions affording abutment surfaces against which the movable leaf of the hinge reacts as a lever to lift the outer end of the distance link as the cover of the cabinet is being closed, thereby preventing the upper edge of the leaf from pressing or rubbing against the cabinet-top.

In the accompanying drawings, Fig. 1 is a side elevation of the hinge in open position, fragments of the cabinet-top and swinging cover being shown in section. Fig. 2 is a similar view showing the lever action of the movable leaf of the hinge as it lifts the distance link when the hinge is being closed. Fig. 3 is a similar view showing the hinge closed. Fig. 4 is an end elevation of the hinge in closed position as shown in Fig. 3. Fig. 5 is a top plan view of the hinge opened 180°, and Fig. 6 is a view similar to Fig. 3 but showing the hinge in section to reveal the distance link in side elevation.

In the preferred embodiment of the invention, as illustrated, the hinge comprises a stationary leaf 1 and a movable leaf 2 which are pivotally connected together by means of the distance link 3. The stationary leaf 1 comprises a piece of sheet-metal folded at 4 to provide the spaced parallel vertical walls 5, 5, the lower extremities of which are bent outwardly in opposite directions to form the attaching ears 6, 6. This leaf of the hinge is adapted to be seated within a suitable vertical slot 7 cut inwardly from the end edge of the top-board *a* of the cabinet. The upper edges 8, 8 of the walls 5, 5 are substantially straight throughout the major portion of their length and are set substantially flush with the upper surface 9 of said top-board *a*.

The spaced walls 5, 5 are preferably provided at their outer corners with slight upward extensions affording the slightly raised abutment surfaces 10, 10. For the sake of clearness, the elevation of the surfaces 10 above the surface 9 of the top-board *A* is exaggerated in the drawing. In practice the difference in elevation between the surfaces 9 and 10 may be approximately 1/64 of an inch and is wholly unobjectionable. The outer or exposed ends 11 of the walls 5, 5, opposite the fold 4, are curved to match and set flush with the ogee or other finishing

curve at the end of the top-board *a*. The ears 6 are let into suitable depressions in the under surface of the board *a*.

The movable leaf 2 of the hinge is also formed of sheet-metal which is folded at 12 to form the spaced walls 13, 13, extensions of which are further bent to form the attaching ears 14, 14, lying in a common plane with which the fold 12 makes an acute angle. The walls 13 of the movable leaf are set into a vertical slot 15 cut in the cover *b* and the outer ends of said walls, including the extension ears 16, are curved to set flush with the ogee curve or other finish at the hinge end of the cover *b*.

The distance link 3 is pivoted upon the pin 17 between the walls 5 of the stationary leaf 1, and is formed with a movement limiting slot 18 which is curved concentrically with the pivot pin 17 and through which passes the pin 19. In the specific embodiment of the invention illustrated, the angular extent of the slot 18 is about 45°. The upper edge 20 of the link 18 is shaped so as to be flush with the surfaces 8 and 10 of the stationary leaf 1 when said link lies horizontally, in which position the outer extremity of the link projects horizontally beyond the end of the board *a* and extends between the end ears 16 of the walls 13 of the movable leaf 2, being pivotally connected to the latter at 21. The lower edge 20' of the distance link, is curved to match the ogee curves of both the table-top and cover boards, as shown in Figs. 2, 3 and 6.

When the cover *b* is opened to the position shown in Fig. 1, the extreme upper edge of said cover is substantially at the level of the upper surface of the top-board *a*. As the cover is being closed the corners 22 at the outer ends of the folds between the ears 14 and walls 13 strike the abutment surfaces 10 of the stationary leaf 1, as shown in Fig. 2, and act as the fulcrum of a lever formed by the hinge-leaf 2 to lift or swing the distance link 3 upwardly about its pivot 17, thereby elevating the pivot 21 and cover *b* to the position shown in Fig. 3. The metallic contact between the corner 22 and the upper edges of the walls 5 prevents rubbing of the edge of the cover *b* against the upper surface of the cabinet-top *a*.

It will be noted that in the position shown in Fig. 3 the movable leaf 2 is disposed mainly between the stationary leaf 1 and the pivotal connection 21. In other words, the pivotal connection 21 is disposed nearer the upper than the lower limit of the movable leaf. Further, the slot in the movable leaf is open for a space of more than 180° around the pivotal connection 21. These provisions permit the movable leaf to be swung through an angle of substantially 270° from the position shown in Fig. 3 to that shown in Fig. 1.

The invention is not to be understood as limited to the exact form and arrangement of parts shown and described, as the present construction is obviously susceptible of material modifications within the scope of the invention as defined in the appended claims.

Having thus set forth the nature of the invention, what I claim herein is—

1. A hinge comprising stationary and movable leaves, and a link-bar connection between said leaves, one of said leaves being constructed and adapted to react as a lever against the other leaf to lift the link-bar and effect the elevation of the movable leaf as the latter is being swung from open to closed position.

2. A hinge comprising a stationary leaf having a surface adapted to be set substantially flush with the upper surface of a table-top member, a movable leaf having a surface adapted to be set substantially flush with the surface of a cover member, and a link-bar connection between said leaves, one of said leaves having a portion projecting slightly beyond the said surface which is adapted to be set flush with its supporting member, such projecting portion serving to coact with the other leaf independently of said link-bar to prevent contact of the cover with the table-top as said cover is being swung between open and closed positions.

3. A hinge comprising a stationary leaf, a movable leaf disposed above the stationary leaf, and a link-bar pivotally connected at its opposite ends to said leaves, the movable leaf being disposed mainly between the stationary leaf and the point of pivotal connection of the link-bar with the movable leaf, said movable leaf being formed with a slot to receive the link-bar, which slot is open for a space of more than 180° about said pivotal connection, thereby permitting the movable leaf to be opened through an angle of substantially 270° to a pendant position at one end of the stationary leaf.

4. A hinge comprising a stationary sheet-metal leaf adapted to be received within a vertical slot in a table-top and having spaced parallel walls connected by an inwardly and vertically disposed fold, and also having horizontally disposed attaching ears bent outwardly in opposite directions at the lower extremities of said parallel walls and adapted to be set flush with the under surface of the table-top, a movable leaf adapted to be disposed in a slot in a cover and having spaced parallel walls connected by an inwardly disposed fold inclined to the vertical, said movable leaf also having horizontally arranged attaching ears bent outwardly in opposite directions at the lower extremities of said parallel walls and adapted to be set flush with the under surface of the cover.

face of said cover when in closed position above the table-top, and a link-bar pivotally connected at its opposite ends to said leaves and received between said spaced
5 walls.

5. A hinge comprising a stationary leaf adapted to be secured to a table top-board, a movable leaf adapted to be secured to a

table cover-board, a link-bar pivoted at its opposite ends to said leaves and inclined to 10 the vertical when said leaves are in superposed relation.

In testimony whereof, I have signed my name to this specification.

EMIL A. KOPF.
